UNITED STATES PATENT OFFICE.

EDWARD S. SMITH, OF OVID, MICHIGAN.

VEHICLE-SPRING.

SPECIFICATION forming part of Letters Patent No. 293,801, dated February 19, 1884.

Application filed May 29, 1883. (No model.)

To all whom it may concern:

Be it known that I, EDWARD S. SMITH, of Ovid, county of Clinton, State of Michigan, have invented a new and useful Improvement 5 in Torsion-Springs for Vehicles; and I declare the following to be a full, clear, and exact description of the invention, such as will enable others skilled in the art to which it pertains to make and use it, reference being had to the 10 accompanying drawings, which form a part of this specification.

My invention consists in the combinations of devices and appliances hereinafter specified, and more particularly pointed out in the claim.

15 In the drawings, Figure 1 is an inverted plan of an apparatus embodying my invention. Fig. 2 is a side elevation. Fig. 3 is a perspective view of some of the parts.

20 My invention relates to torsion-springs for vehicles, and has for its object an improved construction of springs of this character which shall give increased elasticity, and thus afford an easy-riding vehicle. I accomplish this object by securing to the body of the vehicle torsion-springs connected at their extremities 25 with suitable side springs, said side springs secured at their opposite extremities to an equalizer, the construction being such as to afford an unobstructed motion to the body as the 30 springs are operated.

To this end, as illustrated in the drawings, A represents the body of the vehicle.

B represents the side bars.

C represents the front head-block.

35 D represents the rear axle.

E and E' represent the equalizers, secured at their extremities in any proper manner to the side bars.

40 F and F' represent torsion-springs, constructed of bars of suitable metal, each of said bars extending across the vehicle-body, and preferably projecting beyond the body at each side, said bars or springs secured to the body at a suitable distance in front and at the rear of the 45 middle of the body. Each of said bars or springs is secured to the center sill, a, of the vehicle-body by a suitable bearing, f, secured thereto, the bearing being so constructed as to hold the bar stationary at this point, which may 50 be accomplished by constructing the bearing with a squared orifice to receive the squared bar, as shown, or in any other suitable manner. The torsion-spring is also secured to the side sills of the body a by proper bearings, f', the

construction being such that the torsion-spring 55 may have a free motion in said bearings, which may be accomplished, for instance, by rounding the bar at these points and constructing the bearings to correspond therewith, as shown.

G and G' represent front and rear side 60 springs, constructed in any suitable manner, and firmly connected at their inner extremities with the front and rear torsion-springs, respectively, in such a manner that a strain upon the side springs will be communicated to 65 the torsion-springs. As shown, the side springs are provided with bearings g and g', connected thereto, the bars or torsion-springs 70 being squared at their extremities, the bearings being constructed in a corresponding manner, so as to hold the torsion-springs from turning in the bearings. At the opposite extremities the side springs are connected at the front and rear of the vehicle to the front and rear equalizers, E and E', in any suitable manner. 75 I prefer to locate these side springs outside of the body and inside the side bars.

The operation of the device will be readily understood.

80 A vehicle provided with springs constructed as herein described presents a neat appearance. The springs are found to be very elastic, while, also, there is less side motion than is the case with side-spring vehicles as commonly constructed.

85 Instead of securing the front and rear extremities of the side springs to the equalizers E and E', they may be, if preferred, secured directly in any proper manner to the running-gear of the vehicle.

90 What I claim is—

95 In a side-bar vehicle provided with front and rear equalizers, the combination, with the vehicle-body, of front and rear torsion-springs rigidly secured to the body intermediate of their length, and provided with loose bearings f' at the edges of the body, and a front and rear pair of side springs, having one of their ends connected with the ends of the torsion-springs, their opposite ends being connected with the equalizer, substantially as described.

100 In testimony whereof I sign this specification in the presence of two witnesses.

EDWARD S. SMITH.
